UNITED STATES PATENT OFFICE.

ERNEST E. CRANE, OF CHICAGO, ILLINOIS, ASSIGNOR TO AMERICAN MANGANESE STEEL COMPANY, OF AUGUSTA, MAINE, A CORPORATION OF MAINE.

DRIVING-SHEAVE FOR STEAM-SHOVELS.

1,231,856.

Specification of Letters Patent. Patented July 3, 1917.

Application filed July 6, 1916. Serial No. 107,765.

To all whom it may concern:

Be it known that I, ERNEST E. CRANE, a citizen of the United States, and a resident of Chicago, in the county of Cook and State 5 of Illinois, have made and invented certain new and useful Improvements in Driving-Sheaves for Steam-Shovels, of which the following is a specification.

This invention relates to driving sheaves 10 such as are used upon steam shovels, dipper dredges, and similar machines.

A sheave, such as is used for driving cables and chains, is necessarily exposed to considerable wear, ordinarily requiring the frequent replacement of the sheaves, a somewhat costly and troublesome procedure. In order to overcome this, sheaves have been formed of extremely hard material, such as manganese steel, the initial cost of which, 20 however, is considerable, and the large amount of expensive metal contained in the worn-out sheave when the same is scrapped, more than offsets the advantages derived from the additional length of life of the sheave. It is therefore the purpose of the present invention to provide a sheave wherein the parts which are subject to wear are formed of extremely hard and serviceable material, such as manganese steel, and, furthermore, these parts are so constructed and arranged that they may be replaced from time to time as they become worn.

A further object is to accomplish the aforementioned ends in a practical and expeditious manner, the various parts being so designed that the rivets or other holding means whereby the removable parts are secured in place are protected against wear and also free from high and excessive driving strains.

Other objects and advantages will appear as the description proceeds, wherein it is to be understood that changes in the precise embodiment of the invention can be made within the scope of what is claimed without departing from the spirit thereof.

In the drawings, the preferred embodiment of my invention is illustrated, wherein:

Figure 1 is a side view partly in section along a diametric plane of a sheave embodying the characteristic features of my invention;

Fig. 2 is a section on line 2—2 of Fig. 1. Referring specifically to the several views,

the sheave is formed with the usual hub 5, 55 spokes or webs 6, and grooved rim 7.

A wearing liner or supplemental rim 8, preferably formed of manganese steel or other extremely hard wearing material, is positioned within the grooved rim 7 of the 60 sheave, and is formed in sections, each section being securely held within the grooved rim by the rivets or holding screws 9. These rivets or holding screws extend through the outstanding and radial walls 10 65 of the supplemental rim or liner, and through the corresponding walls 11 of the rim of the sheave. The radial walls 10 of the wearing liner are provided with the countersunk openings 12 in which the head 70 13 of the holding rivets or screws, seats, thus allowing the holding rivets or screws to terminate flush with the surface of the wearing liner, and preventing their contact with the rope or chain which extends 75 around the sheave.

The supplemental rim or wearing liner 8 is provided with the outstanding symmetrically spaced lugs 14 which, projecting centrally from the radial walls of the wearing 80 liner, define driving teeth adapted to engage a chain, and transmit power thereto, although it is to be understood in this connection that I do not limit my invention to any particular form of teeth or lugs, as the 85 same may vary according to the character of the chain or cable which is to be driven. The hub of the sheave 5 is formed with a key slot 15, whereby power may be transmitted from the shaft upon which the sheave 90 is mounted, to the rim 7, and in order that this power may be transmitted to the wearing liner without subjecting the holding means 9 to such stresses, the sections of the wearing liner are provided with the notches 95 16. The notches 16 are located directly beneath the driving teeth 14 and the rim of the sheave is provided with suitable lugs or projections 17, which fit within the notches aforementioned, and provide for the direct 100 transmission of power between the rim of the sheave and the wearing liner. The notches and projections of the two rims being located directly beneath the driving teeth 14, provide for the direct transmission 105 of power to the latter, and a further advantage arising from this location of the notches resides in the fact that the removal of metal

from the wearing liner does not weaken the liner, due to the excess of metal at these points by the presence of the driving teeth or lugs 14.

- 5 The tension of the cable or chain which extends around the sheave holds the supplemental rim or wearing liners in position and prevents undue strains from being brought to bear upon the holding rivets 9.
- 10 After the liner has become worn beyond use the rivets 9 are removed and a new liner inserted in place. This repair, although made at a small cost, is equivalent to the substitution of an entirely new sheave.
- 15 What I claim is:—

A driving sheave comprising a hub and a grooved rim supported thereby having out-

standing side walls, a segmental liner fitting within said grooved rim, said grooved rim being provided with spaced out-standing lugs, said liner being provided with notches receiving said lugs therein and driving teeth formed upon said liner radially outward from said notches and adapted to reinforce and strengthen the liner adjacent said notches and further providing for the forced driving of a flexible element. 20 25

Signed at Chicago, in the county of Cook and State of Illinois, this 28th day of June, A. D. 1916.

ERNEST E. CRANE.
